CLAIM

The ornamental design for a combined ground station and case for unmanned aerial vehicle, as shown and described.

DESCRIPTION

FIG. 1 is a perspective view of a combined ground station and case for unmanned aerial vehicle showing our design in a closed configuration.

FIG. 2 is another perspective view thereof.

FIG. 3 is a left side view thereof.

FIG. 4 is a right side view thereof.

FIG. 5 is a front view thereof.

FIG. 6 is a back view thereof.

FIG. 7 is a top view thereof.

FIG. 8 is a bottom view thereof.

FIG. 9 is a perspective view of the combined ground station and case for unmanned aerial vehicle in an open configuration shown in an open configuration.

FIG. 10 is another perspective view thereof.

FIG. 11 is a left side view thereof.

FIG. 12 is a right side view thereof.

FIG. 13 is a back view thereof.

FIG. 14 is a front view thereof.

FIG. 15 is a top view thereof; and,

FIG. 16 is a bottom view thereof.

The broken lines in the drawings represent unclaimed environmental subject matter and form no part of the claim.

1 Claim, 14 Drawing Sheets
